CASING FOR A GLASS CHILLER

Marvin Cooper, New Rochelle, N.Y., assignor to Dynamic Classics, Ltd., New York, N.Y., a corporation of New York

Filed Aug. 15, 1967, Ser. No. 8,271

Term of patent 3½ years

(Cl. D44—29)

FIG. 2

FIG. 5

FIG. 1 is a top plan view of a casing for a glass chiller showing my new design;

FIG. 2 is a front elevational view;

FIG. 3 is a right side elevational view;

FIG. 4 is a rear elevational view; and

FIG. 5 is a fragmentary sectional view taken on line 5—5 of FIG. 2.

I claim:

The ornamental design for a casing for a glass chiller, as shown.
